UNITED STATES PATENT OFFICE

171,161

COMBINED DISPLAY AND PROTECTIVE DEVICE FOR A TELEPHONE RECEIVER OR SIMILAR ARTICLE

Le Roy E. Larabell, Detroit, Mich.

Application December 4, 1951, Serial No. 17,605

Term of patent 14 years

(Cl. D1—2)

To all whom it may concern:

Be it known that I, Le Roy E. Larabell, a citizen of the United States, residing at 4421 Fairview, Detroit, Michigan, have invented a new, original, and ornamental Design for a Combined Display and Protective Device for a Telephone Receiver or Similar Article, of which the following is a specification, reference being had to the accompanying drawing, forming a part thereof.

Figure 1 is a side elevational view of a combined display and protective device for a telephone receiver or similar article embodying my new design.

Figure 2 is a top plan view.

Figure 3 is a bottom plan view thereof.

The broken lines are for illustrative purposes only.

I claim:

The ornamental design for a combined display

and protective device for a telephone receiver or similar article, substantially as shown and described.

LE ROY E. LARABELL.
